UNITED STATES PATENT OFFICE.

ANDREW BUTCHART WALLACE AND HERBERT JOHN JONES, OF MASTERTON, NEW ZEALAND.

TOUCH-REGULATOR FOR PIANOS.

No. 843,721.

Specification of Letters Patent.

Patented Feb. 12, 1907.

Application filed November 23, 1905. Serial No. 288,769.

To all whom it may concern:

Be it known that we, ANDREW BUTCHART WALLACE, of Wagner Cottage, Perry street, Masterton, in the Colony of New Zealand, and HERBERT JOHN JONES, of Opaki Road, Landsdowne, Masterton, aforesaid, both subjects of His Majesty the King of Great Britain and Ireland, have invented certain new and useful Improvements in Touch-Regulators for Pianos, of which the following is a specification.

This invention relates to the class of apparatus employed for improving the technique of pianoforte-players.

The invention consists of apparatus designed to be applied to the keys of a pianoforte of ordinary construction whereby said keys are operated upon to render it necessary for the player to exert pressure above normal to depress the keys, the amount of extra pressure required being regulatable to suit the particular player and the circumstances, and thereby develop the muscles and increase the suppleness of a player's hands and fingers.

Referring to the accompanying drawings, Figure 1 is a side sectional elevation; Fig. 2, a plan; Fig. 3, an enlarged side sectional elevation; Fig. 4, a corresponding front sectional elevation; Fig. 5, a plan of same; and Fig. 6, a plan of one end of the rocking shaft.

The rocking shaft 1 is tubular and is journaled at one end 2 in the frame 3 of the piano and at its opposite end has a projecting pin 4, which is journaled in the end of a bracket 5, secured to the frame of the piano, said bracket being constructed so that it may be sprung away from the spindle when it is desired to remove the rocking shaft. The wire 35 springs 22 project from the rocking shaft and bear upon the key-levers, there being one spring for each key-lever. Upon the middle of the rocking shaft is secured the lever-arm 6, to the end of which is connected the end of a tubular connecting-rod 7, which is internally screw-threaded to receive the similarly-screwed end of the remaining part 8 of the connecting-rod. By this arrangement the length of the connecting-rod may be adjusted as required to bring the required amount of initial pressure upon the key-levers.

The lower end of the connecting-rod is pivotally connected to one arm of a bell-crank lever 9, which vibrates in a vertical plane and is pivotally mounted at 10 in a bracket 11, secured beneath the keyboard of the piano. To the other arm of this bell-crank lever is pivoted one end of a link 13, the opposite end of which is connected in a similar manner to the arm 14 of a bell-crank lever which vibrates in a horizontal plane and is pivoted at 15 in the bracket 11. The other arm 16 of this bell-crank extends toward the front of the piano and has a screwed end 17, which fits into a socket 18, having a head 19, which is tapered to serve as a pointer.

The head is slotted to receive a quadrant-bracket 20, which is screwed beneath the keyboard of the piano, and a set-pin 21, screwing through the under side of the head, 70 can be employed to clamp the lever in any desired position relatively to the quadrant. The quadrant has markings upon it to indicate different positions of the lever to produce different pressures of these springs upon 75 the key-levers.

In the drawings the springs are secured to the rocking shaft by passing them through holes drilled therein and riveting or soldering them in position. This is only one of a large 80 number of ways which could be employed by any ordinary mechanic for effecting the purpose.

What we do claim, and desire to secure by Letters Patent of the United States, is— 85

Apparatus for the purpose indicated comprising in combination, a tubular rocking shaft journaled within the casing of a piano, springs having one end projecting from the rocking shaft and their other ends passed 90 through the rocking shaft and secured thereto, key-levers upon which the springs bear, a lever projecting from the rocking shaft, a vertically-vibrating bell-crank lever pivoted below the keyboard, a connecting-rod coupling together the rocking-shaft lever and the vertical bell-crank lever, a horizontally-vibrating bell-crank lever, a link connecting 95 together the vertical and horizontal bell-crank levers, an arm of the horizontal bell-crank 100 lever extending toward the front of the piano and having a screwed end, a socket screwed

upon the end of the said arm, a slotted head having a tapered end, a quadrant-bracket having indication-markings and adapted to pass within the slotted head, and a set-pin for clamping the head to the quadrant substantially as described.

5 In testimony whereof we have signed our

names to this specification in the presence of two witnesses.

ANDREW BUTCHART WALLACE.
HERBERT JOHN JONES.
